No. 36,760.

Patented January 26, 1904.

UNITED STATES PATENT OFFICE.

HERBERT J. STRAKER, OF NORTH ATTLEBORO, MASSACHUSETTS, ASSIGNOR TO GEORGE K. WEBSTER, OF NORTH ATTLEBORO, MASSACHUSETTS.

DESIGN FOR A BACK FOR BRUSHES, MIRRORS, OR SIMILAR ARTICLES.

SPECIFICATION forming part of Design No. 36,760, dated January 26, 1904.

Application filed December 26, 1903. Serial No. 186,757. Term of patent 3½ years.

To all whom it may concern:

Be it known that I, HERBERT J. STRAKER, a citizen of the United States, residing at North Attleboro, in the county of Bristol and State of Massachusetts, have invented a certain new, original, and ornamental Design for the Back of a Brush, Mirror, or Similar Article, of which the following is a specification, reference being had therein to the accompanying drawing.

The drawing represents a face view of the back of a brush embodying my new design.

What I claim is—

The ornamental design for the back of a brush, mirror, or similar article, as herein shown.

HERBERT J. STRAKER.
